UNITED STATES PATENT OFFICE.

SIGMOND HANDLER, OF NEW YORK, N. Y.

ADJUSTABLE SEAT.

Application filed March 8, 1922. Serial No. 542,021.

To all whom it may concern:

Be it known that I, SIGMOND HANDLER, a citizen of the United States, and a resident of the borough of Manhattan, in the city and 5 State of New York, have invented certain new and useful Improvements in Adjustable Seats, of which the following is a specification.

The invention relates to adjustable and 10 folding seats, such as are used in automobiles and the like, or as camp stools, and has for its principal object to provide an article of the kind mentioned, which is capable of being folded up into a small and compact 15 form, so as to occupy little space in storage and to be easily carried from one place to another, to be easily and quickly unfolded, and to be adjustable in several different heights or positions, and which 20 shall also be of light weight but of sufficiently strong construction to support such strain as is liable to be applied to the same.

The invention consists in the novel construction, arrangement and combination of 25 various devices, elements and parts, as hereinafter set forth in the claims hereof, one embodiment of the same being illustrated in the accompanying drawings and described in this specification.

30 In the accompanying drawings, Fig. 1 is a side elevation showing the chair in its lowest operative position;

Fig. 2 is a similar view showing the chair in a somewhat higher position;

35 Fig. 3 is a similar view showing the chair in its highest position;

Fig. 4 is a front view, on an enlarged scale, of the chair, showing it in the same position as in Fig. 2;

40 Fig. 5 is a side view of the chair showing the same folded up into its smallest form; and

Fig. 6 is a detail view, which will be hereinafter more particularly referred to.

45 In carrying my invention into effect in the embodiment thereof which I have selected for the purpose of illustration in the accompanying drawings and description in this specification, I provide a chair which 50 when in either of its extended or operative positions, is automatically locked against accidental closing, and which is therefore perfectly secure, even when a heavy weight is placed upon the seat of the same, and 55 which nevertheless requires but a few simple

movements to fold the same into its compact or inoperative position.

In the construction of my invention in this selected form or embodiment, I provide a base frame of rectangular form, designated 60 11, having on each side, near the rear, a stop 12. At the front corners of the frame are pivotally secured legs 13, which when the chair is in use extend upward and backward for supporting the rear part of the chair 65 seat. Resting on the frame, but not secured thereto, are legs 20, one at each side, which extend upward and forward for supporting the front part of the chair seat.

The seat of the chair comprises a frame 70 25 of rectangular form, bearing a cushion 26. The frame is provided on each side with a notch 27.

The upper ends of the legs 13 are pivotally secured to the frame 25 by means of 75 toggle levers 15 and 16, and the upper ends of the legs 20 are pivotally secured to the frame 25 by links 22. The legs 13 and 20 on each side are pivotally secured together near their middle at 21.

The back of the chair comprises a frame 30, a cushion 31, and a pair of downwardly extending members 32, each of which has a forwardly projecting toe at its lower end, which engages under the seat frame 25 when 35 the chair is opened up. The members 32 are pivotally secured at 34 to a pair of L-shaped members 33 on the seat frame 25.

The operation of my invention will be 40 readily seen from an inspection of the drawings. It will be observed that in the opened up position shown in Figs. 1 and 2 the lower ends of the legs 20 are prevented from slipping backward by the stop 12, while in the position shown in Fig. 3, in which the ends 45 of the legs are brought nearer together for the purpose of making the seat higher, the legs are held in position by the engagement of the upper ends of the legs 13 with the notch 27 in the seat frame. The operation 50 100 and function of the links 15, 16, and 22, will be readily seen from an examination of the views shown in Figs. 1, 2 and 3.

The advantages of my invention will be 55 obvious from what has been above said 105 with regard to its construction and operation.

I do not limit myself to the exact details of 60 construction shown and described, as it is 110 obvious that various modifications of the

same may be made without departing from the spirit and scope of my invention.

Having thus described my invention, what I claim as new and desire to secure by Letters Patent is as follows:

1. A device of the character described, comprising in combination a seat, a back pivotally secured to said seat, means adapted to maintain said back in upright position when in use, a pair of legs adapted to support one part of said seat, a second pair of legs adapted to support another part of said seat, a leg of one pair being crossed over a leg of the other pair and pivotally secured thereto, the upper ends of one pair of said legs being swingingly connected with said seat, and a pair of toggle-levers, each having one end swingingly connected to the upper end of one of the other pair of said legs and the other end swingingly connected to said seat.
2. A device of the character described, comprising in combination a seat, a back pivotally secured to said seat, means adapted to maintain said back in upright position when in use, a pair of legs adapted to support one part of said seat, a second pair of legs adapted to support another part of said seat, a leg of one pair being crossed over a leg of the other pair and pivotally secured thereto, the upper ends of one pair of said legs being swingingly connected with said seat, and a pair of toggle-levers, each having one end swingingly connected to the upper end of one of the other pair of said legs and the other end swingingly connected to said seat.

over a leg of the other pair and pivotally secured thereto, a pair of links swingingly connected to the upper ends of one pair of said legs and to said seat, and a pair of toggle-levers swingingly connected to the upper ends of the other pair of said legs and to said seat.

3. A device of the character described, comprising in combination a seat, a back pivotally secured to said seat, means adapted to maintain said back in upright position when in use, a base frame, a pair of legs pivotally secured to said base frame and adapted to support a part of said seat, toggle levers on each side adapted to pivotally secure the upper ends of said legs to said seat, a pair of stops on said base frame, a pair of legs adapted to engage with said stops and to support another portion of said seat, a pair of links, one on each side, adapted to pivotally secure the upper ends of said second pair of legs to said seat, a leg of one pair being crossed over and pivotally secured to a leg of the other pair, and a notch on the under side of said seat adapted to engage the upper end of one of said legs.

In witness whereof I have hereunto signed my name this 7th day of March, 1922.

SIGMOND HANDLER.
